SHEET FEEDING MECHANISM FOR
PRINTING MACHINES

William K. Eckhard, Dunellen, N. J., assignor, by
mesne assignments, to R. Hoe & Co., Inc., New
York, N. Y., a corporation of New York

Application March 15, 1933, Serial No. 660,812

10 Claims. (Cl. 271—54)

This invention relates to registering mechanism for printing machines adapted to print on sheet metal, pasteboard and similar materials, having for its object the provision of an improved sheet registering mechanism which will insure the correction of any misalignment which may occur to a sheet before being presented to the grippers of an impression cylinder.

Another object is to provide in sheet registering mechanism of the character indicated, means for guiding the front edge of a sheet and presenting it in proper alignment to the grippers on the impression cylinder, so that the front or leading edge of the sheet is advanced parallel to the axes of the plate and impression cylinders of the mechanism, the grippers then acting upon the sheet to clamp it in accurate register and finally to thrust same between the plate and impression cylinders while maintaining the said sheet in accurate register.

It is also an object of the invention to provide a sheet registering mechanism of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in the precise embodiment of the invention herein disclosed may be made within the scope of what is claimed without departing from the spirit of the invention.

The preferred embodiment of the invention is illustrated in the accompanying drawings, wherein:

Figure 1 is a fragmentary view, partly in section, of a printing machine with its front frame removed and with certain of the transverse members in cross section, showing a sheet engaged by the novel sheet aligning mechanism forming the principal feature of the present invention;

Figure 2 is a view similar to Figure 1, showing the sheet in the position in which it is engaged by the grippers and disengaged by the sheet aligning members;

Figure 3 is an elevational view, with parts broken away, as seen in the direction of the arrow 3 of Figure 1, showing one side of the machine and one of the sheet aligning members, which latter is duplicated on the other side of the machine;

Figure 4 is a view taken on line 4—4 of Figure 2, partly in section, looking in the direction of the arrow; and

Figure 5 is a transverse sectional view, taken on line 5—5 of Figure 4, as seen in the direction of the arrow, showing certain details of construction.

Referring now to the drawings: 11 designates the frame of a printing machine having cross members 11' and 11" and 12 a supporting surface or table adjustably fastened in any suitable manner to the lower brace member 11" and over which sheets 13 travel or are pushed, as herein-after described.

On the frame 11, plate and impression cylinders 14, 15 respectively are rotatably mounted, the cylinder 15 having grippers 16 provided with adjustable registering faces or stops 17 which engage the front edge of the sheet.

The grippers 16 are fastened to a shaft 18 and are operated by a cam 19 secured to the frame 11. The cam 19 coacts with a roller 21 carried on an arm 22 also secured to the shaft 18.

The front guides or sheet aligning members which form an important feature of the present invention, each comprises a bracket or plate 23 adjustably secured to the brace member 11'. A cam plate 23' is fastened to the bracket 23, the cam plate 23' having a slot 24 formed with an upwardly directed or cam portion as at 25 for a purpose which will appear hereinafter.

A shoe or slider 26 riding on the cam plate 23' has two pins 27, 28, the former of which serves as a pivot for an element hereinafter described. A crank member 29 pivoted on the pin 27 has a stud 31 engaged in the slot 24 and is also provided with a reciprocating guide or sheet aligning member 32 having a hooked end 33 forming a sheet abutment which directly engages a sheet 13 as the latter is thrust forward by the sheet pushing means mentioned below. The said hook 33 of the sheet aligning member 32, as will be seen by the details set forth hereinafter, serves as a reciprocating abutment against which the advancing sheet is first aligned and then confined between same and the sheet pusher means of the mechanism, the said sheet then being advanced in parallelism with the axes of the plate and impression cylinders.

An upper portion 34 of the pivoted crank member 29 has secured thereto one end of a stem 34' slidably supported at another end on an extension or lug formed on the slider 26. On the stem 34', a spring 35 is arranged, the spring 35 being confined between the upper portion 34 of the pivoted

crank member 29 and the extension of the slider 26, and exerting a pressure tending to turn the said crank member in a counterclockwise direction. A link 36 is pivotally connected by the pin 5 28 to the slider 26, and is also hinged to an arm 37 which is adjustably fastened to another arm 37' secured to a shaft 38, supported in bearing brackets 20, joined to the brace member 11' and having keyed or otherwise suitably secured there- 10 to a lever arm 39 to which an upper end of a link 41 is pivotally connected. The lower end of the link 41 is pivotally secured to an extension 42 of a bell crank lever 43 pivoted to the front frame 11, as shown in Figure 3, and acted upon by a spring- 15 pressed plunger indicated generally at 44 which is slidably supported in a post 44' secured to the frame 11. The bell crank lever 43 has a roller 45 which is engaged with a cam 46 secured to a hub 51 fastened to the main shaft 47, the normal 20 action of the plunger 44 tending to turn the crank lever 43 in a counterclockwise direction and, consequently, to force the roller 45 into engagement with the cam 46. The cam 46 is provided with slots 46' in which ride bolts 49 that are fastened to the hub 51 mentioned above. The said slots 46' and bolts 49 permit the turning or adjustment of the cam 46 relatively to the hub 51, thereby advancing or retarding the action or position of the sheet aligning mechanism.

30 The pusher means indicated generally by the number 48, a pair of which are customarily employed for moving forward the sheets, may be of the type shown in patent of Eckhard for Sheet feeding mechanism No. 1,888,659, dated November 22, 1932, and in patent to Hunting, No. 1,941,093, dated December 26, 1933, for Sheet feeding mechanism for printing machines, and need not be described in detail here.

It is to be understood that the sheet-aligning 40 assembly forming the feature of the present invention and denoted generally by the reference character A is duplicated at each side of the frame, each assembly being operatively connected to the shaft 38 in the manner illustrated.

45 The step by step progress of a sheet by the conveying mechanism of the printing mechanism before reaching the pushers 48 may be of the general character described in the above-referred to patents of Eckhard and Hunting and need not be set forth in detail here.

50 After the sheet has been carried forward to a point adjacent the pusher means 48, the latter rise up behind the rear edge of the sheet and engages same thereby pushing same forward over the table 12 until it is engaged by the hooks or abutments 33 of the reciprocating sheet aligning members 32 prior to engagement with the gripper means 16 of the impression cylinder 15. The said sheet 13 will now advance forward while 55 engaged at its trailing end by the spring pressed pushers 48, and at its leading end by the hooks of the reciprocating sheet aligning members 32 mentioned above until the faces or stops 17 of the grippers 16 on the impression cylinder 15 engage the leading end of the sheet, the said sheet aligning members 32 then withdrawing from the sheet as the grippers.

55 Figures 1 and 2 show the progressive position of a sheet after being engaged and moved along in proper alignment by the pushers 48 and the front guide or sheet aligning members together. It will be observed that in Figure 1 the stud 31 of the spring biased crank member 29 has completed its movement to the right in the slot 24, the roller 70 75 45 of the spring pressed crank lever 43 now

abutting against the extremity of the depressed area of the cam 46 which through the instrumentality of the other coacting parts including links 41 and 39, shaft 38, arm 37, link 36 and the reciprocating slider 26 to the crank member 29 is hinged, will have moved the sheet aligning member 32 to the position shown in Figure 1 where it is operative to engage and preliminarily register a sheet 13. In Figure 2, the roller 45 has passed on to the raised portion of the cam 46, thereby 10 moving the coacting parts and, consequently, the crank member 29 to the left, the stud 31 of the said crank member 29 meanwhile having passed into the upwardly directed portion 25 of the slot 24 thereby angling upwardly the sheet aligning member 32 and disengaging the hooked end or abutment 33 of the aligning member from the sheet 13 as the grippers 16 engage same. By the provision of the said sheet aligning mechanism in accordance with the present invention, it is to 15 be noted the front edge of the sheet, and consequently, the sheet itself, if advancing misaligned, will be correctly aligned by the sheet aligning members 32 as it is being pushed forward by the pushing mechanism, and then held in proper alignment until engaged with the gripper stops 17. The grippers then press back on the sheet and the reciprocating abutments or sheet aligning members rise out of the way. This correcting 20 action of the sheet aligning members 32 insures the advancing of the front or leading edge of the sheet until it is engaged by the registering faces 17 of the grippers 16. During the forward movement of the sheet towards the plate and impression cylinders, the sheet pusher means 48 may 25 travel at substantially the same rate as the sheet aligning members 32 for a distance equal to the length of the straight portion of the slot 24, the movement of the pusher means and sheet aligners being timed so that the sheet 13 will overtake the 30 gripper faces 17. By inspection of Figure 2, it will be seen that the sheet pusher means 48 has continued to advance the sheet 13 and press same against the registering faces or stops 17 of the sheet grippers, after the withdrawal of the sheet 35 aligning members 32, the rate of travel of the spring pressed pushers 48 now being slightly in excess of the grippers 16 which at the moment are turning with the cam actuated gripper shaft 18 in a direction opposite to that of the cylinder 40 45 50 55 60 65 70 75 80 85 90 95 100 105 110 115 120 125 130 135 140 145 150 155 160 165 170 175 180 185 190 195 200 205 its trailing edge to urge it forward, a plurality of reciprocating abutments adapted to simultaneously engage the forward edge of the sheet and hold it parallel with the axes of the cylinders, 5 and means for regulating the operation of the abutments so that they may engage with and be disengaged from the forward edge of the sheet at various predetermined times.

2. In a sheet registering mechanism for a machine having cylinders adapted to print on relatively stiff material, means engaging the sheet on its trailing edge to urge it forward, a plurality of reciprocating abutments adapted to simultaneously engage the forward edge of the sheet and 10 hold it parallel with longitudinal axes of the cylinders, and means for variably timing the action of the reciprocating abutments so that they may be engaged with and disengaged from the forward edge of the sheet at various predetermined 15 times.

3. In sheet feeding mechanism for a printing machine, including printing cylinders having sheet grippers, a track adapted to support a sheet and sheet pushers arranged to travel over said 20 track and directly engaging the trailing edge of said sheet; a member reciprocatingly mounted on said machine, a sheet engaging abutment hinged to said member, and means for variably controlling the action of the member so that the 25 movement of the abutment may be timed to engage at a predetermined position on said track, the front edge of the sheet being thrust forward by the sheet pushers, said abutment then moving out of engagement with the front edge of the sheet 30 35 when said grippers engage the sheet.

4. In sheet feeding mechanism for a printing machine, including printing cylinders having sheet gripping means, a track adapted to support a sheet, and sheet pushers arranged to travel over said track and directly engage the trailing edge of said sheet; a member reciprocatingly mounted on and bodily movable relatively to said machine, a plurality of sheet engaging members hinged to said first mentioned member, and 40 means for controlling the movement of the sheet engaging member so that said sheet will be preliminarily engaged and aligned by the sheet engaging members, said sheet engaging members then moving uninterruptedly forward in step 45 with said sheet pushers and guiding said sheet forwardly toward said printing cylinders in proper alignment therewith to a point where said sheet grippers engage the sheet, said sheet engaging members then withdrawing from the sheet while 50 the sheet gripping means guide the said sheet 55 operatively between the said printing cylinders.

5. In a printing machine of the class described having printing and impression cylinders provided with sheet gripping means, sheet pusher means, 60 a feed table adapted to support a sheet and coactable with said grippers and pusher means, said pusher means directly contacting the trailing edge of said sheet, the combination with said cylinders, grippers, feed table and pusher means, 65 of a member directly coactable and uninterruptedly moving forward with said pusher means for engaging leading and trailing ends of the sheet whereby said sheet may be conveyed over the feed table so that the front edge of the sheet 70 may be maintained in proper alignment relative to the printing and impression cylinders preparatory to engagement with the grippers, said gripping means engaging said sheet at a predetermined time preparatory to guiding same between 75 the said printing and impression cylinders, and

cam actuated means for variably timing the uninterrupted movement of the said member.

6. In a device of the character described having printing cylinders provided with sheet grippers, a feed table coactable with said grippers, 5 and pusher means adapted to engage the trailing edge of and thrust forwardly in the line of progress a sheet deposited on said table, said pusher means acting to thrust a sheet forwardly into engagement with a reciprocating member 10 mounted on and bodily movable relatively to said device, said member and pushing means, then uninterruptedly advancing forwardly together to convey said sheet in a forward direction, said grippers engaging the forward edge of said 15 sheet at a predetermined position on the feed table while said reciprocating member is disengaging from the sheet.

7. In sheet feeding mechanism of the character described having printing instrumentalities, sheet pushing means and sheet gripper means; the combination with the sheet pushing and sheet gripper means, of a plurality of sheet aligning members movably mounted on reciprocating means secured to the mechanism and coactable with the sheet pushing means to operatively engage and correctly align a leading edge of said sheet, said pushing means being in direct contact with the trailing edge of the sheet, a rotary carrier, a cam adjustably mounted on said carrier and connected to said reciprocating means for variably moving the sheet aligning members to disengage same from said sheet, said gripper means then engaging the said leading edge of the sheet and drawing same in a forward direction into the printing instrumentalities. 30 35

8. In a printing machine having plate and impression cylinders, the combination with sheet feeding mechanism having a reciprocating pusher device, sheet gripping means and a track for the pusher device, said track being adapted to support a sheet; of a sheet aligning member reciprocatingly mounted on said feeding mechanism and timed to coact with said pusher device in first aligning a sheet thrust forward by the pusher device and then moving forward with the pusher device while the trailing edge and the leading edge of the sheet is confined between the said pusher device and the said sheet aligning member, said sheet being advanced to a point where the sheet gripping means engages the sheet and the draws same forwardly between said plate and impression cylinders in correct alignment for accurate printing, and means including a rotating adjustable cam for variably moving the sheet aligning member to engage with and be disengaged from the leading edge of the sheet at various predetermined times. 40 45 50 55

9. In a sheet registering mechanism for a machine having cylinders adapted to print on relatively stiff material, means engaging the sheet on its trailing edge to urge it forward, a plurality of reciprocating abutments adapted to simultaneously engage the forward edge of the sheet and hold it parallel with longitudinal axes of the cylinders, members secured to the mechanism, slots formed in the members, said slots having cam portions, shoes riding in said slots and pivotally connected to said abutments, and means for variably timing the action of the reciprocating abutments so that they may be engaged with and disengaged from the forward edge of the sheet at various predetermined times. 60 65 70 75

10. In sheet feeding mechanism for a printing 75

machine having a printing cylinder provided with sheet gripping means, a track adapted to support a sheet, and a pusher arranged to travel over said track and adapted to abut against the 5 trailing edge of the sheet and urge said sheet forwardly; a member reciprocatingly mounted on said machine, sheet aligning mechanism connected to said member and adapted to engage a front edge of the sheet thrust forward by the 10 pusher, said sheet aligning mechanism main-

taining the front edge of the sheet in correct alignment relatively to the printing cylinders and moving uninterruptedly forward with said sheet until same is engaged with the sheet gripping means, and means for advancing or retarding the time of engagement of the sheet aligning mechanism relatively to the front edge of the sheet.

WILLIAM K. ECKHARD. 10
